UNITED STATES PATENT OFFICE.

L. SOLON GROUT, OF CHICAGO, ILLINOIS.

DESIGN FOR A WATCH-SIGN.

SPECIFICATION forming part of Design No. 12,564, dated November 1, 1881.

Application filed September 24, 1881. Term of patent 3½ years.

To all whom it may concern:

Be it known that I, L. SOLON GROUT, a citizen of the United States, residing at Chicago, in the county of Cook and State of Illinois, 5 have invented a certain new and original Design for a Watch-Sign; and I do hereby declare that the following is a full, clear, and exact description thereof, reference being had to the accompanying drawing, and to the letters of reference marked thereon, which form a part of this specification.

The drawing represents an elevation of one side of my watch-sign.

The leading feature of my design consists in 15 a sign made to represent a watch, provided at each side with an ornamental scroll, upon which any letters or words may be painted, a ring that serves for hanging the sign up by and connected to the sign by a pendant that represents a human hand which grasps said ring, 20 and with a spectacle-frame to the bottom of said sign.

A is the disk, painted on each side to represent an open-face watch; B B, an ornamental scroll on each side of the watch, having the names of articles of merchandise or other words 25 painted thereon. C is the pendant, formed in the shape of a hand that grasps the ring D, and E the frame of a pair of spectacles.

30 The parts may be made of wood or metal, or both, in a suitable manner.

This sign is tastefully finished in colors and gold-leaf, and has the same appearance from either side.

What I claim is—

1. The design for a watch-sign, the same consisting of the ornamental scrolls B B, secured to the sides of the disk A, representing an open-face watch, and adapted to have painted on their surfaces any words or figures, substantially as described and shown. 40

2. The design of a watch-sign, the same consisting of the ornamental scrolls B B, secured to the sides of a disk, A, representing an open-face watch that has an engraved rim, all as 45 shown and described.

3. The design for a watch-sign herein shown and described, the same consisting of the ornamental scrolls B B, secured to the sides of a disk, A, representing an open-face watch, 50 and of an imitation of a spectacle-frame, E, to the bottom of said disk.

4. The design for a watch-sign herein shown and described, consisting of the ornamental scrolls B B, secured to the sides of a disk, A, representing an open-face watch, of an imitation of a spectacle-frame, E, to the bottom of said disk, and of a pendant, C, representing a human hand that grasps the ring D by which 55 the sign is suspended. 60

In testimony that I claim the foregoing as my invention I affix my signature in presence of two witnesses.

L. SOLON GROUT.
